UNITED STATES PATENT OFFICE

JOSEPH M. MINTEER, OF CANFIELD, OHIO

MUSICAL INSTRUMENT

Application filed May 31, 1930. Serial No. 458,273.

This invention appertains to improvements in musical instruments generally and more particularly to a wind reed type thereof.

An object of the invention is to provide a musical instrument of the class set forth which will preferably be blow operated only and so constructed as to be readily and easily taken apart for cleaning purposes as well as for the quick repair and replacement of its parts.

Another object of the invention resides in the provision of a piano type of key board for the actuation of the reed control valves, the tones of the C major diatonic scale being indicated by white keys and sharps and flats by black keys in an arrangement corresponding to that of the same tonal control keys of a piano.

A further object of the invention lies in the provision of a bodily movable key board of the type mentioned, whereby the same may be easily and quickly adjusted to different positions relative to the reed control valves and whereby to change from one key to another.

Still another object of the invention is to provide a novel form of reed chamber which may be readily and easily removed and replaced from and into operative position for cleaning and repair purposes as well as a control valve structure for each reed chamber employed, the several reed control valves being mounted in a simple but effective manner whereby they may be quickly adjusted, removed and replaced without a complete take down of the instrument in its entirety or the immediately associated parts of the valve operated mechanisms.

With the foregoing and other equally important objects and advantages in view, the invention resides in the certain new and useful combination, construction and arrangement of parts as will be hereinafter more fully described, set forth in the appended claims and illustrated in the accompanying drawings, in which:

Figure 1 is a top plan view of a practical embodiment of the improved musical instrument;

Figure 2 is a side elevation thereof;

Figure 3 is a fragmentary side elevation of the blow end of the instrument and showing the key board adjusted to a different position from that of the same in Figures 1 and 2;

Figure 4 is an end elevation;

Figure 5 is an enlarged vertical transverse sectional view, taken on the line 5—5 of Figure 2;

Figure 6 is a fragmentary horizontal longitudinal section through the body or air chamber of the instrument;

Figure 7 is a perspective view of one of the reed chambers per se;

Figure 8 is a view similar to that of Figure 7 but showing one of the control valves per se; and

Figure 9 is another similar view of the key board supporting and adjusting rod per se.

Referring to the drawings, wherein like characters of reference designate corresponding parts in the several views thereof, the embodiment of the invention as shown therein by way of example only, is constituted in a hollow tubular body 10 having its forward end flared, as at 11, to substantially bell form and its rearwardly directed end of a reduced diameter, as at 12, for the attachment thereto of a mouth piece 13. The forward end of the interior of the body 10 is preferably closed by a wall 14 at a point immediately adjacent the bell portion 11 thereof.

Projecting from one side of the intermediate portion of the body 10 are a plurality of tubular members 15, which are alternately arranged in staggered relation lengthwise thereof and have their inner connected ends opening into the interior of the same, with their outer ends open and all disposed in a common plane.

These tubular members 15 each constitutes a support or seat for a tubular reed chamber 16, which projects inwardly through the same and well into the interior of the body 10. The reed chambers 16 are each of a somewhat less diameter than the interior diameter of the tubular members or supports 15, and has its open end projected through a supporting collar 17 which is formed to provide an inwardly directed reduced portion of a diameter

suitable to frictionally seat in the one end of a member or support 15 or to be screw threaded, as at 18, for removably secured engagement therein as desired. The outer 5 larger or flanged end of each collar 17 is preferably of a diameter slightly greater than the interior diameter of a member or support 15, in order to abut the outer end edge thereof, when the reed chamber 16 is in place and 10 to form a finger grip to facilitate the removal and replacement of the latter from and to operative position, as required.

Each of the reed chambers 16, inwardly of the collar 17 carried thereby is longitudinally slotted, as at 19 for an intermediate 15 distance between the latter and its inner end and the same is normally closed by a reed 20 secured at one end, preferably the upper or outer end, as at 20', to the outer side of the 20 reed chamber in the case of a blow type of tone producing reed or on the inner side thereof in a draw type.

Extending tangentially from the outer side of the body 10 from points adjacent the opposite 25 ends of the rows of members or supports 15 are a pair of parallel brackets 21 having their outer ends transversely apertured to support a rod 22 therein.

Pivoted at their inner ends on this rod 22 30 in side to side relation are a series of keys 23 and 23', the keys 23 being white and the keys 23' being black after the manner and arrangement of the corresponding keys of a piano. These keys are preferably less in 35 number than the number of reed chambers 16, and are mounted on the rod 22 between a pair of collars 24, arranged in spaced apart relation thereon between the brackets 21, which collars 24 act as stops to limit the longitudinal 40 movements of the rod 22 in the latter and also hold the keys in proper position.

The rearwardly directed end of the rod 22 is provided with a knob or finger piece 25 while the intervening portion, between the 45 knob or finger piece and the adjacent of the collars 24 and forwardly of the rear bracket, is provided with a series of notches 26 for the cooperation therewith of a detent 27 mounted on the latter bracket.

By this arrangement the rod 22, together 50 with the keys 23 and 23', is shiftable in the brackets 21 with respect to the body 10 and the reed chambers 16, in order to change the key of the instrument, as for instance C, B-flat and A, etc.

Associated with each of the reed tubes 16 and normally closing the outer open ends thereof is a valve 28, (similar to a saxophone or clarinet type thereof) which consists of a 60 cup-shaped metal disk 28 in which may be placed an ordinary saxophone pad 29 having its inner face abutting for air-tight seating engagement on the opposed reed tube end and an arm 30 extending from its outer face. The 65 free end of the arm 30 is tubular for adjust-

able engagement on the free end of a form of bell crank or lever 32. Each of the valve arms 30 is provided with a set screw or the like 31, by means of which it will be adjustably secured in place on the adjacent end of a companion lever 32.

The several levers 32 are pivotally mounted, as at 33, on a supporting rod 34 extending between the brackets 21, the point of pivot of each lever 32 being substantially at the bend of the angled arms 32' and 32'' thereon. The lever arm 32' has its free end formed to provide an enlarged flat portion 32a which is arranged to abut the lower side of a companion key 23 or 23' of the key board of the instrument.

A coil spring 35 is cooperative with each lever 32 to constantly urge the same in a direction that the companion valve 28 will be seated on the open end of the complemental of the reed tube 16. For this purpose the spring 35 has one of its ends bearing against the lower side of the arm 32'' of the bell crank or lever 32 and its other end against the inner side of a second rod 36 extending between the brackets 21 beneath the pivot rod 34.

In the use of the instrument as thus constructed and arranged, the air chamber or interior of the body 10 will be supplied with air from the mouth piece 13 in a usual manner and it is controlled by the valves 28 at the outer ends of the reed chambers 16. When a key 23 or 23' is depressed, a companion valve 28 will be lifted from the outer open end of the complemental of the reed chambers 16 so that air from the interior of the body 10 will pass from a tubular member 15 by the reed 20 and into the chamber 16. With the passing of the air in this manner, the particular reed 20 will be vibrated and will produce the tone to which it is tuned. When a key 23' or 23 is depressed, it forces down on the enlargement 32a of the valve lever 32 and swings the latter on the pivot rod 34, causing it to lift the valve 28 associated therewith and simultaneously the associated spring 35 placed under tension. When the key is released the spring 35 immediately acts to return the parts to normal position.

With the key board set at one key position, the supporting rod 22 may be adjusted in the brackets 21 to shift the key board to a different key position as will be well understood. With the use of the blow reeds, in the manner of the mounting of the same as herein described, the tones will come direct from the reed chambers 16 and not from the bell end 115 of the instrument.

In carrying out the objects and purposes of the present invention, it is to be noted that any number of octaves in the musical scale may be employed other than the two shown, and the reeds may be of either the blow or draw type or each reed chamber 16 may be provided with both a blow and draw type of

reed, but, in the latter case, the reeds would have to be tuned to the same pitch. The use of the blow type of reed is to be much preferred, however, if only for sanitary reasons.

Without further description, it is thought that the features and advantages of the invention will be readily apparent to those skilled in the art, and it will of course be understood that changes in the form, proportion and minor details of construction may be resorted to, without departing from the spirit of the invention or its scope as claimed.

I claim:

1. In a musical instrument, a hollow body, an air inlet at one end of said body, reed chambers positioned in a side wall of said body and opening outwardly thereof, control valves normally closing the outer ends of said reed chambers, spaced parallel brackets projecting from one side of said body, a rod mounted in said brackets, keys commonly pivoted on said rod for selectively actuating said control valves and means for releasing said rod for endwise adjustment in said brackets whereby to shift said keys relatively to certain of said control valves to change the key of the instrument.

2. In a musical instrument, an elongated hollow body, a mouth piece at one end of said body, reed chambers positioned in the side wall of said body and opening outwardly thereof, control valves normally closing the outer ends of said reed chambers, spaced parallel brackets projecting from one side of said body to either side of said reed chambers, a rod mounted for endwise movement in said brackets, keys commonly pivoted on said rod for selectively actuating said control valves, and means carried by one of said brackets for normally holding said rod against movement, said means being releasable to allow the adjustment of said rod to move said keys relatively to said control valves to change the key of the instrument.

3. In a musical instrument, a hollow body, an air inlet at one end of said body, tubular outlets in longitudinal alinement at one side of said body, reed chambers removably screw threaded inwardly of the outer ends of said tubular members and opening outwardly thereof, control valves normally closing said reed chambers and means for selectively actuating said control valves.

4. In a musical instrument, a hollow body, an air inlet at one end of said member, reed chambers arranged in longitudinal alinement at one side of said body, control valves normally closing the outer end of said reed chambers, keys pivotally mounted on said body adjacent said control valves, levers pivotally mounted on said body for cooperation with said keys and the actuation of said valves, and means for detachably mounting said valves on said levers.

5. In a musical instrument a hollow body, an air inlet at one end of said body, reed chambers arranged in longitudinal alignment at one side of said body, control valves normally closing the outer end of said reed chambers and having levers pivotally mounted on said body, a rod carried by said body and having a plurality of keys pivotally mounted thereon, and means for selectively shifting said rod and keys into operative relation with certain of said levers.

6. In a musical instrument a hollow body, an air inlet at one end of said body, reed chambers arranged in longitudinal alignment at one side of said body, control valves normally closing the outer end of said reed chambers and having levers pivotally mounted on said body, a rod carried by said body and having a plurality of keys pivotally mounted thereon, means for selectively shifting said rod and keys into operative relation with certain of said levers, and detent means for securing said rod and keys in adjusted position.

JOSEPH M. MINTEER.
